UNITED STATES PATENT OFFICE.

ALBERT J. DAVIS, OF PERTH AMBOY, NEW JERSEY.

FRICITION-WHEEL.

SPECIFICATION forming part of Letters Patent No. 482,788, dated September 20, 1892.

Application filed March 10 1892. Serial No. 424,400. (No model.)

To all whom it may concern:

Be it known that I, ALBERT J. DAVIS, a citizen of the United States, residing at Perth Amboy, Middlesex county, New Jersey, have 5 invented certain new and useful Improvements in Friction-Wheels, fully described and represented in the following specification and the accompanying drawings, forming a part of the same.

10 The object of this invention is to facilitate the renewal of the wooden blocks which are commonly used in contact with a metallic cone to produce friction in a friction-wheel, and the invention is shown herein applied to the 15 drum of a hoisting-machine. In such hoisting-machines it is common to arrange the drum and driving gear-wheel upon the same shaft and provide each with a portion of the 20 friction-wheel, the gear being rotated continuously and a spring being used to press the drum and gear-wheel normally apart, and the drum being pressed against the gear-wheel by suitable means when the drum is to be rotated.

25 In the drawings, Figure 1 is a longitudinal section of the drum and friction devices with the parts shown in section where hatched. Fig. 2 is an edge view of the detachable ring for the wooden blocks, and Fig. 3 is a face view of the same with the blocks inserted in 30 one-half of the periphery and cross-lines *d d* to indicate the division of the ring.

35 A is the drum-shaft, and B the spring inserted between the drum D and the hub of the gear-wheel G. The gear-wheel is formed with a disk K, upon which is detachably mounted a ring E, to the exterior of which the wooden blocks *w* are applied. The outsides of the blocks are turned in conical form, and a hollow metallic cone C is formed upon the 40 end of the drum to fit the same. In Fig. 1 the drum is shown pressed with the cone in contact with the blocks. The ring E is of cylindrical shape and provided with a series of dovetails *G'*, between which the blocks *w*, 45 grooved each upon its two inner corners to fit such dovetails, are driven tightly, as shown at the right-hand side of Fig. 3, the blocks being omitted from the remainder of the ring to

show the construction of the plate *E'*, by which the ring is attached to the disk K. This plate 50 is turned to fit a recess *L* in the face of the disk, and is thus accurately centered with the shaft A. Bracket-ribs *j* are shown upon the inner side of the ring and plate to stiffen the ring, and the plate is formed with bolt-holes 55 *i* between the ribs. The plate is secured to the disk by bolts *h*, fitted through the holes, so that it may be readily removed and a similar plate and ring substituted therefor.

The plate and ring are divided diametrically, as shown at *d* in Fig. 3, to adapt the plate for removal from its position between the gear-wheel G and the drum D without removing either from the shaft A by slipping the drum or gear-wheel endwise and removing the halves of the ring separately after first removing the bolts *h*, which can be done from the exterior of the gear-wheel.

I am aware of the state of the art disclosed by United States Patents No. 260,791, of July 11, 1882; No. 304,300, of September 2, 1884; No. 408,011, of July 30, 1889, and No. 461,929, of October 27, 1891, and I hereby disclaim the same, limiting myself to the construction herein specifically shown, described, and claimed. 75

What I claim as my invention, and desire to secure by Letters Patent, is—

The combination, with the hoisting-drum D, provided with the hollow cone C, of the gear-wheel G, provided with disk K, having 80 the recess L therein, and the ring E, having the plate *E'*, divided into two parts and fitted to such recess and provided externally with the metallic dovetails *G'* and with the wooden blocks *w*, grooved each upon its two inner corners to fit such dovetails and tapered externally to fit the cone C, as and for the purpose set forth.

In testimony whereof I have hereunto set my hand in the presence of two subscribing 90 witnesses.

ALBERT J. DAVIS.
